UNITED STATES PATENT OFFICE.

JACOB ULLRICH, OF HOBOKEN, NEW JERSEY.

FOUNTAIN-PEN.

SPECIFICATION forming part of Letters Patent No. 365,953, dated July 5, 1887.

Application filed March 11, 1887. Serial No. 230,483. (No model.)

To all whom it may concern:

Be it known that I, JACOB ULLRICH, of Hoboken, in the county of Hudson, State of New Jersey, have invented certain new and useful 5 Improvements in Fountain-Pens, of which the following is a specification.

The object of my invention is to provide a new and improved fountain-pen in which the ink flows steadily and easily, and which pen 10 does not require any shaking for the purpose of causing the ink to flow.

The invention consists in the combination, with the usual tubular stem for receiving the ink, of a tip or feeder having a projecting end 15 resting against the under side of the pen, which tip has a longitudinal groove extending from the front to a short distance from the rear end, and at the rear end a slot is provided which connects the said groove with a V-shaped recess in the opposite side of the inner part of 20 the tip.

The invention also consists of a clip held on the upper surface of the pen for the purpose of retaining the ink on the upper surface of 25 the pen.

In the accompanying drawings, Figure 1 is a longitudinal sectional view of my improved fountain-pen. Fig. 2 is a front view of that side of the tip facing the pen. Fig. 3 is a rear 30 view of the same opposite the one resting against the under side of the pen.

Similar letters of reference indicate corresponding parts.

The tip A is inserted in the tube B, screwed 35 in one end of the tubular reservoir or handle C, containing the ink. Said tube A has its inner end, A', made cylindrical, and its front end is pointed or tapered. That face of the tip that is pointed is provided with a longitudinal groove, D, which extends from a short 40 distance from the point of the tip to a short distance from the inner end, and serves to conduct the ink to the tip of the pen. At the rear end of said groove said tip is provided with the slot E, which connects the rear end of the groove 45 D with the V-shaped recess F on the rear part of the tip, and on that surface or side oppo-

site the one provided with the groove D. Said V-shaped recess F also decreases in depth from the inner end of the tip toward the outer end, 50 as shown in Fig. 1. The ink flows and passes into the widest part of the V-shaped recess F, then through the slot E into the groove D, and flows through the same to the tip of the pen L. As the recess E gradually decreases 55 in cross-section, and is widest at the inner end of the tip, it is not apt to become clogged with the ink. The ink can thus readily pass from the recess into the slot F, and from the same to the groove D, the capillary attraction of the 60 slot and groove serving to draw the ink to the front end of the tip. The ink passes from the groove of the tip to the point of the pen, which is held in the usual manner in the holder. A metal or rubber clip, H, may be held on the 65 top of the pen to retain the ink on the upper surface of the pen.

I am aware that tips have been provided with the longitudinal grooves and with slots; but I have found that in most cases the ink-conductor becomes clogged, requiring shaking of the pen to cause the ink to flow, or requiring some sudden or abrupt movement, which is not necessary in my improved tip.

Having thus described my invention, I claim 75 as new and desire to secure by Letters Patent—

A fountain-pen provided with a tip having a longitudinal groove in one side, a slot at the inner end of said groove, and a recess in the inner end of the tip in that side opposite the 80 one provided with the groove, which recess decreases in depth and width from the inner to the outer end of the tip, said recess being in communication with the groove by means of the above-mentioned slot, substantially as 85 shown and described.

In testimony that I claim the foregoing as my invention I have signed my name in presence of two subscribing witnesses.

JACOB ULLRICH.
